UNITED STATES PATENT OFFICE.

JENNIE A. HENDEE, OF MARIETTA, ILLINOIS, ASSIGNOR OF ONE-HALF TO LEWIS B. HENDEE, OF MARIETTA, ILLINOIS.

STOVE-LID LIFTER.

1,241,378.

Specification of Letters Patent. Patented Sept. 25, 1917.

Application filed February 16, 1916. Serial No. 78,705.

To all whom it may concern:

Be it known that I, JENNIE A. HENDEE, a citizen of the United States, residing at Marietta, in the county of Fulton and State 5 of Illinois, have invented new and useful Improvements in Stove-Lid Lifters, of which the following is a specification.

The primary object of this invention resides in the provision of a stove lid lifter 10 which shall be simple in construction, durable in use, well adapted for the purposes intended, and wherein the lifter may at all times be readily and easily engaged with the stove lid.

15 Another object of the invention is the provision of a spring for automatically moving the active ends of the lifter to an open position after the lifting operation of the lid is performed.

20 With the above and other objects in view, the invention consists in the novel features, details of construction, and combination of parts which will hereinafter be more fully set forth, illustrated in the accompanying 25 drawings and pointed out in the appended claim.

Figure 1 is a side elevation of the stove lid lifter illustrated in lid lifting action;

Fig. 2 is a similar view illustrating the 30 lifter in inactive position;

Fig. 3 is a top plan view of one of the tongs of the lifter.

Referring more particularly to the accompanying drawings, in which like characters 35 of reference refer to corresponding parts in the several views, 5 designates my improved type of stove lid lifter comprising an upper cross tong 6 and a lower cross tong 7, the said upper cross tong being provided with a shank

40 portion 8 having an elongated longitudinally disposed slot 9 for pivotally receiving the shank portion 10 of the lowermost cross tong 7. The lower cross tong 7 is pivotally connected within the slot 9 of the uppermost 45 cross tong 6 through the medium of a pivotal pin 11 which passes through the side walls 12, forming the slot 9 and through the shank of the lowermost cross tong 7. The free end of the lowermost tong, or the clamp- 50 ing end thereof at its point of intersection with the shank 10 is offset laterally and bowed upwardly in opposite directions as at 13 to present an abutment shoulder 14, and as will be seen when the tongs are in

assembled position the abutment shoulder 55 14 upon the clamping action of the tongs will engage with the side walls 12 forming the slot 9, of the uppermost tong member 6. Each of the tong members 6 and 7 further constitutes a handle portion 16 and 17 re- 60 spectively. The handle portion 16 is of hollow form and is provided with air holes 18 preventing the heating of the handle 16 when the tongs are utilized for lifting heated stove lids and the like. This tong member 6 aside from being bowed throughout its longitudinal length is formed with a pair of closed side flanges 19 depending from the lower edge of the handle and its shank 8 to provide opposed guide flanges whereby 70 during the clamping action of the tongs the said flanges perform the function of preventing any loose or slight lateral movements thereof. The handle 17 of the lowermost tong 7 is also slightly bowed for the 75 full transverse extent thereof and is provided at its inner end with a downwardly and forwardly beveled portion 20, said portion being adapted to engage a correspondingly formed shoulder 21 of the handle 16 80 whereby during the completion of the lifting action of the stove lid the portion 20 will engage with the wall 21, through the medium of the spring 22 and limit the opening of the tongs whereby the active ends 15 85 of the tong members will be at all times retained in position to easily, quickly and accurately engage themselves with the stove lid 23. It will be apparent from the disclosure of the drawing that this spring 22 90 causes an automatic opening of the clamping ends 15 of the tongs and comprises a coiled spring having its upper end connected with the inner surface of the top portion 24 95 of the uppermost tong 6 and has its lowermost end 25 seated within a notch formed in the upper surface of the lowermost tong 7.

From the foregoing description, taken in connection with the accompanying drawing, the advantages of construction and of 100 the method of operation will be readily apparent to those skilled in the art to which the invention relates, and while I have described the principles of operation of the invention together with the device which 105 I now consider to be the best embodiment thereof, I desire to have it understood that the device shown is merely illustrative and

that such advantages may be made when desired as are within the scope of the claim appended hereto.

I claim:

- 5 A stove lid lifter embodying upper and lower crossed tong members, the said lower tong member being provided at its inner end with a downwardly and inwardly beveled portion, a coil spring connected at one end with the inner wall of the upper tong member and the opposite end of said spring being seated in a notch formed in the inner wall of the lower tong member, said spring tending to automatically open the
- 10

clamping ends of the tong members and 15 force the downwardly and forwardly beveled extremity of the lower tong member into engagement with a correspondingly formed shoulder on the inner extremity of the upper tong member for limiting the 20 opening action of the tongs, substantially as and for the purpose specified.

In testimony whereof I affix my signature in presence of two witnesses.

JENNIE A. HENDEE.
